DOOR LOCK

John H. Roethel, Coral Gables, Fla., assignor to Roethel Engineering Corporation, Detroit, Mich., a corporation of Michigan

Application August 20, 1953, Serial No. 375,430

9 Claims. (Cl. 292—280)

This invention relates to a latch mechanism for swinging doors, particularly the doors of automobiles or other vehicle bodies, an object of the invention being to provide an improved door latch mechanism which is characterized by its simplicity and compactness in construction and which is relatively small in size, economical to manufacture, comparatively quiet in operation and efficient in use.

More particularly the present invention is embodied in an improved door latch mechanism having a rotatable latch member, a pivoted dog or detent cooperable therewith, and shiftable detent release means mounted on a supporting plate or the like at the jamb edge of the door, the detent release means being operable from the outside of the door and being rendered inoperative to release or disengage the detent by means of a movable blocking member mounted preferably on a flange extending angularly from the inner edge of the supporting plate, said blocking member being movable preferably by an inner manually operable means into and out of blocking relation to the release means. In the one embodiment of the invention, the blocking member not only blocks disengagement of the detent through actuation of the release means from the outside of the door but also renders the inside remote control means inoperative to release the detent.

Further characteristics of the latch mechanism in accordance with the embodiments of the present invention herein illustrated by way of example may be briefly summarized as follows: The rotatable latch bolt is mounted on the plate portion and has a series of tooth-like projections extending entirely around the periphery thereof. A detent engaging latch device is secured to the latch bolt and is mounted to turn or rotate about the same axis as the bolt and has a series of abutments corresponding to the tooth-like projections on the bolt. A detent means is pivotally mounted on the plate portion and has a plurality of arms, one of which is engageable with any one of the latch device abutments. The detent release means preferably, although not necessarily comprises a lever having a plurality of arms, the lever being pivotally mounted on the plate portion to swing about the pivotal axis of the detent means on a common pivot means and having a part disposed in opposing relation to a part of one of the detent arms so that movement of the release lever in one direction will cause corresponding movement of the detent. The part on the release lever and the part on the detent arm are not interlocked thus permitting pivotal actuation of the detent means independently of the release lever.

This application is a continuation in part of my co-pending applications No. 151,839, filed March 25, 1950, and No. 156,804, filed April 19, 1950, now abandoned.

Further features and objects of the particular embodiments of the invention herein illustrated will appear in the following description, reference being had to the accompanying drawings forming a part of the specification

2

wherein like reference numerals designate corresponding parts in the several views.

Fig. 1 is a sectional elevation taken substantially through lines 1—1 of Fig. 2 looking in the direction of the arrows 5 and illustrating a door lock constructed in accordance with one embodiment of the invention.

Fig. 2 is a section taken substantially through lines 2—2 of Fig. 1 looking in the direction of the arrows.

Fig. 3 is a view in part similar to Fig. 1 illustrating a 10 second embodiment of the present invention.

Fig. 4 is a section taken substantially through lines 4—4 of Fig. 3 looking in the direction of the arrows.

Before explaining in detail the present invention it is to be understood that the invention is not limited to the 15 details of construction and arrangement of parts illustrated in the accompanying drawings, since the invention is capable of other embodiments, and of being practiced or carried out in various ways. Also it is to be understood that the phraseology or terminology employed 20 therein is for the purpose of description and not limitation.

In the drawings there is illustrated, by way of example, 25 particular embodiments of the present invention as applied to the doors and frame structures of an automobile body. The latch device embodied in the modification of the invention shown in Figs. 1 and 2 comprises a case plate 10 provided with screw bosses 10a by means of which the case plate 10 is secured to the inner side of the jamb portion or free edge wall of a vehicle door. The 30 case plate 10 terminates at its inner edge in a flange 11 which is adapted to be positioned along the inner panel of the door. The latch device is preferably provided with a rotatable toothed latch or bolt 12 positioned at the outer side of the case plate 10, this latch or bolt having an integral projecting shaft or shank 13 extending through an aperture in the case plate which is formed with a bearing for the bolt shank. The inner end of the shank 13 of the bolt is flattened and extended through a correspondingly shaped aperture in a rotatable toothed detent 40 engaging member or ratchet 14 and is riveted thereto.

The rotatable latch 12, as shown in dotted outline in 45 Fig. 1, is formed with a number of radially projecting tooth-like projections 12a, preferably six, which are spaced equally around the periphery of the latch so as to provide in effect a gear type latch or bolt. The toothed member 14 is also formed around its periphery with a number of tooth-like abutments or projections 14a which correspond in number to the tooth-like projections 12a of the latch bolt.

Pivoted on a shoulder rivet 15 secured to the case plate 10 is a swinging detent, pawl or dog 16 which has a downwardly projecting detent arm 17 cooperable with any one of the projections 14a of the ratchet member 14. The detent arm 17 is engageable with any 55 one of the projections 14a in the manner shown in Fig. 1 to hold the toothed ratchet member and, hence, the bolt 12 in locking position against rotation in a clockwise direction as viewed in Fig. 1. The detent 16 is also provided with an upwardly projecting arm or extension 18 and also an inwardly extending arm or extension 19. Thus, the detent in the embodiment herein shown is provided with three arms 17, 18 and 19, and is preferably formed from a piece of flat metal stock.

Associated with detent 16 is a detent actuating lever 60 20 which is pivoted at its lower end upon the shoulder rivet 15 so as to turn or swing about the axis of the detent 16. The release lever 20 has an outwardly extending arm 21 terminating in a lateral flange 21a positioned for engagement by a plunger or the like 22 which may be shifted inwardly to swing the lever 20 on its pivot 15 by any suitable manually operable means on the outside

of the door such, for example, as a handle or by any other preferred means such as a push button associated with an outside door handle.

The detent arm 17 is yieldingly urged toward the toothed member 14 and the detent release lever 20 is urged outwardly toward its retracted position shown in Fig. 1 by means of a common spring 23. This spring has a substantially horizontally extending arm 23a engaging the detent arm 17 and has an upper spirally wound coiled portion 23b secured at 24 to the case plate 10. It will be noted that the release lever 20 overlies the detent 16 and has its inner edge abutting against a lug or projection 18a on the detent. Hence, the effort exerted by the spring 23 in urging the detent arm 17 into engagement with the ratchet member 14, as shown in Fig. 1, will also be transmitted through the lug 18a to the release lever 20, thereby urging the latter toward its retracted position. The final retracted position of the release lever 20 is determined by a stop 10b in the form of a lug struck up from the upper edge of the case plate 10 and positioned to engage the release lever arm 21. The release lever 20, for a purpose hereinafter described, has an extension 25 and an arm 26 projecting in the direction of the case plate flange 11.

The latch device constructed in accordance with the present embodiment preferably incorporates a remote control mechanism for permitting release or disengagement of the detent 16 by operation of an inside door handle or other manually operable means. This mechanism is preferably manually actuated from the inside of the door remote from the case plate 10 by means of a door handle which may be turned in the desired direction. Suitably connected to the inside door handle is a longitudinally extending draft link 27 which is pivoted at 28 to the lower end of one arm 29 of a bell crank lever 30. This bell crank lever 30 is pivoted at 31 to the case plate flange 11 and is provided with a projecting arm 32 overlying at its outer end the detent arm 19 and also the release lever arm 26. Normally when the inside door handle is turned so as to swing the bell crank lever arm 32 downwardly, the latter by engagement with the detent arm 19 will swing the detent in a clockwise direction as viewed in Fig. 1, thus swinging the detent arm 17 upwardly from the position shown in Fig. 1 so as to disengage the detent from the member 14. It will be noted that in the present embodiment, the detent arm 19 could be eliminated since downward movement of the bell crank arm 32 will cause the same to engage the detent release lever arm 26 and swing the detent release lever 20 in a clockwise direction as viewed in Fig. 1. The detent 16 by virtue of the abutting relationship of its part 18a with the arm 21 of the detent release lever 20 would also be swung in a clockwise direction thereby having its arm 17 swung out of engagement with the ratchet member 14. This action is similar to that which occurs when the release lever 20 is swung inwardly by operation of the outside door handle, push button or the like, the motion of the release lever being transmitted to the detent through the lug 18a.

In the present embodiment means is provided for rendering the detent release lever 20 inoperative to disengage the detent 16, such as by blocking the same so that the door cannot be opened from the outside. This is accomplished through the medium of a pivoted member 33 mounted on the case plate 11 by means of the pivot stud 31. The pivoted member 33 is provided with an arm 34 extending in a generally horizontal direction toward the case plate 10. The arm 34 lies above the arm 32 of the remote control bell crank 30 and has a portion embossed outwardly from the case plate flange 11 which embossed portion 34a can be positioned in opposing relation to the projection 25 on the detent release lever so as to block swinging movement of the release lever 20. The end of the arm 34 has a lug 34b turned toward the case plate flange 11 and engageable therewith, as

shown in Fig. 1, to prevent bending of the embossed portion 34a under pressure of the release lever 20.

In the present embodiment the pivoted member 33 may be pivotally moved to place the arm 34 in blocking relation to the release lever 20 by means of a vertically shiftable rod or plunger 35. The pivoted member 33 has a portion 36 projecting from the pivotal axis 31 in a direction opposite to the direction in which the arm 34 projects. The vertically shiftable rod or plunger is pivotally connected to this projection or portion 36 at 36a and extends upwardly through the garnish molding at the inner side of the glass panel of the vehicle door. The rod 35 carries at its upper end a knob 37 which may be grasped at the inside of the door to shift the rod or plunger vertically in either direction, thereby rocking the member 33 about its pivotal axis and shifting the arm 34 to position it in blocking relation to the release lever 20 or to restore it to its normal non-blocking position as shown in Fig. 6.

20 The pivoted member 33 is yieldingly held and urged toward its upper and lower limits of movement by means of a snap-over spring 38 of suitable strength attached at one end to the member and at its opposite end to the case plate flange 11. The arm 34 is provided with a lug 39 thereon turned so as to project through an aperture 40 in the case plate flange 11 to provide a positive means for limiting the pivotal movement of the pivoted member 33.

It will be noted that when the embossed portion 34a of the pivoted member arm 34 is in opposing position relative to the release lever arm projection 25, that is, the dotted line position shown in Fig. 1, not only is the outer manually operable means, such as the plunger 22, rendered inoperative to disengage the detent 16 from the ratchet member 14, but the inner manually remote control operable means is also rendered inoperative. That is, the bell crank lever 30 cannot be swung in a counter-clockwise, as viewed in Fig. 2, or detent engaging direction. The arm 26 will block such movement.

40 Latch mechanism of the foregoing construction in which the mechanism may be held against unlatching from either the outside or inside of the door are particularly desirable for use on the rear door of vehicles. Sometimes the objective of locking the rear door, particularly while the vehicle is in motion, is to prevent children from inadvertently unlatching the door and falling out. In the present embodiment the latch mechanism can only be placed in unlocked condition through the push button 37.

The arm 34 of the pivoted member 33 has been described as overlying the bell crank lever arm 32. Thus, if the remote control mechanism to which the draft link 27 is connected is of the type permitting the bell crank to be swung in either direction from its normal position shown in Fig. 2, it will be apparent that the pivoted member 33 could be swung into blocking position without the use of the push button 37. If the bell crank 30 is swung in a clockwise direction, as viewed in Fig. 2, the arm 32 thereof will abut the arm 34 of the pivoted member 33 raising the latter to blocking position. However, it will still be necessary to raise the push button 37 to restore the pivoted member 33 to non-blocking position.

One additional feature of construction not hereinbefore described is the rubber bumper 41 mounted on the case plate 10 at 42 in a position to overlie the upper edge of the detent arm 19. The purpose of the rubber bumper 42 is to provide a resilient cushion against which the detent arm 19 will abut before the detent arm 17 fully returns into engagement with the ratchet teeth 14a after having been disengaged therefrom, thus materially reducing the noise of the engagement of the arm 17 with the ratchet 14.

The embodiment of the invention illustrated in Figs. 3 and 4 is similar in many respects to the embodiment hereinbefore described and all parts thereof similar to the parts in Figs. 1 and 2 have been identified with the same numerals.

In the present embodiment the detent release lever 20 is not provided with an arm corresponding to the arm 26 of the embodiment of Figs. 1 and 2. Thus, when the release lever 20 is blocked by the blocking portion 34a of the blocking member, herein designated 43, only the outer manually operable means is rendered ineffective to release the detent 16 from the ratchet member 14. This is because there is nothing to block swinging movement of the arm 19 of the bell crank lever 30 in a counter-clockwise direction as viewed in Fig. 4. With the exception of the elimination of the arm 26 of the detent release lever 20, all of the other parts of the latch mechanism of the present embodiment mounted on the case plate 10 are similar to those mounted on the case plate 10 of the embodiment of Figs. 1 and 2.

The blocking member 43 of the present embodiment differs somewhat from the previously described blocking member 33, although it does have the arm 34 having the embossed blocking portion 34a. However, the projection 36 of the blocking member 33 is not utilized on the blocking member 43. The blocking member 43 is provided instead with an arm 44 extending below the bell crank arm 32, the arm 44 at the end thereof having a projection 45 extending toward said lower edge of the arm 32.

The present embodiment operates as follows: To position the blocking member 43 so that the blocking portion 34a thereon is in opposing relation to the detent release lever projection 25, the bell crank 30 is swung in a clockwise direction causing the arm 32 thereof to abut embossed or blocking portion 34a and swing the blocking member 43 in a clockwise direction, thereby positioning the blocking member in blocking position. Since the detent release lever 20 in the present embodiment does not have the arm 26, there is nothing to block swinging movement of the bell crank 30 in a counterclockwise direction even though the release lever 20 is blocked against swinging movement by the blocking member 43. Accordingly, the bell crank lever 30 may be swung in such clockwise direction to disengage the detent from the member 14. When the blocking member 43 is in blocking position, the projection 45 on the arm 44 will be in a position immediately underlying the bell crank lever 30 when in its normal position, the position shown in Fig. 4. Thus, if the bell crank 30 is swung in detent disengaging direction, the lower edge of the arm 32 will abut the projection 45 and cause the blocking member 43 to be restored to non-blocking position as limited by the stop 46. The latch mechanism of the present embodiment therefore can always be opened from the inside of the door since only the outer manually operable means is rendered ineffective when the blocking member is placed in blocking position.

I claim:

1. In a door latch mechanism for a swinging door, a support comprising a plate portion for disposition at the door jamb and having a flange extending from the inner edge thereof, a latch bolt mounted on said plate portion to rotate about an axis and having a series of tooth-like projections extending around the periphery thereof, a detent engaging latch device secured to said bolt to rotate therewith about said axis and having a corresponding series of tooth-like abutments, detent means pivotally mounted on said plate portion and engageable with any one of said abutments for holding said bolt in latching position, a lever pivotally mounted on said plate portion and having a part disposed in opposing relation to a part of said detent means, said parts being separate to permit pivotal actuation of the detent means independently of said lever, outer manually operable means for swinging said lever toward said flange to cause said lever part by engagement with said part of the detent means to pivotally actuate the detent means thereby to disengage the same from said latch device, said lever having an arm extending in the direction of the flange, inner manually operable swingable means engageable upon being swung in one direction with said lever arm to swing said lever

toward said flange, a blocking member swingably mounted on said flange and shiftable in one direction into position to block swinging movement of said lever toward the flange, said blocking member and said inner manually operable swingable means being movable independently of each other about a common pivot axis, and manually operable means for shifting said blocking member in said one direction, said directions of movement of said blocking member and said inner manually operable means being counter to each other.

2. In a door latch mechanism for a swinging door, a support comprising a plate portion for disposition at the door jamb and having a flange extending from the inner edge thereof, a latch bolt mounted on said plate portion to rotate about an axis and having a series of tooth-like projections extending around the periphery thereof, a detent engaging latch device secured to said bolt to rotate therewith about said axis and having a corresponding series of tooth-like abutments, detent means pivotally mounted on said plate portion and engageable with any one of said abutments for holding said bolt in latching position, a lever pivotally mounted on said plate portion and having a part disposed in opposing relation to a part of said detent means, said parts being separate to permit pivotal actuation of the detent means independently of said lever, outer manually operable means for swinging said lever toward said flange to cause said lever part by engagement with said part of the detent means to pivotally actuate the detent means thereby to disengage the same from said latch device, inner manually operable swingable means on said flange having a portion engageable with a portion of said lever to swing said lever toward said flange, and blocking means on said flange shiftable into and out of position to block swinging movement of said lever toward said flange, said swingable means and said blocking means being movable independently of each other about a common pivot axis, the direction of movement in which said swingable means is swung to swing said lever being counter to the direction of movement of the blocking means when the latter is shifted into blocking position.

3. In a latch mechanism for a swinging door, a support having a plate portion for disposition at the door jamb, a rotatable latch device mounted on said plate portion, an outer manually operable lever pivotally mounted on said plate portion, a blocking portion on said lever, detent means engageable with said latch device for holding it in door latching position, said detent means being pivotally mounted on said plate portion to swing independently of said lever, said lever at one side of the pivotal axis thereof having a part arranged in opposing relation to a part of said detent means to abut the same at the same side of the pivotal axes of said lever and detent means upon swinging movement of said lever in one rotative direction thereby to pivotally move said detent means in the same rotative direction out of holding position with respect to said latch device, a swingable member on said support having a part movable in a substantially up and down direction, said part having blocking means for cooperation with said blocking portion, an inner manually operable lever pivotally mounted on said support and normally operative when swung in one rotative direction to disengage said detent means from said latch device, said inner manually operable lever having a part arranged in opposing relation to a part of said swingable member to abut the same at the same side of the pivotal axes of said lever and swingable member upon swinging movement of said inner manually operable lever in a second rotative direction thereby to move said swingable member in the same rotative direction to dispose said blocking means in opposing position to said blocking portion, said blocking means when in said opposing position rendering said outer manually operable lever ineffective to move said detent means out of holding position with respect to said latch device.

actuator in one direction thereby to pivotally move said detent means out of holding position with respect to said latch device, a swingable member on said support having a part movable in a substantially up and down direction, said part having blocking means for cooperation with said blocking portion, an inner manually operable lever pivotally mounted on said support and normally operative when swung in one rotative direction to disengage said detent means from said latch device, said inner manually operable lever having a part arranged in opposing relation to a part of said swingable member to abut the same at the same side of the pivotal axes of said lever and swingable member upon swinging movement of said inner manually operable lever in a second rotative direction thereby to move said swingable member in the same rotative direction to dispose said blocking means in opposing position to said blocking portion, said blocking means when in said opposing position rendering said outer manually operable actuator ineffective to move said detent means out of holding position with respect to said latch device.

9. In a latch mechanism for a swinging door, a support having a plate portion for disposition at the door jamb, a rotatable latch device mounted on said plate portion, an outer manually operable actuator mounted on said plate portion, a blocking portion on said actuator, detent means engageable with said latch device for holding it in door latching position, said detent means being pivotally mounted on said plate portion to swing independently of

5 said actuator, said actuator at one side thereof having a part arranged in opposing relation to a part of said detent means to abut the same upon movement of said actuator in one direction thereby to pivotally move said detent means out of holding position with respect to said latch device, a swingable member on said flange having a part movable in a substantially up and down direction, said part having blocking means for cooperation with said blocking portion, an inner manually operable lever 10 pivotally mounted on said flange and normally operative when swung in one rotative direction to disengage said detent means from said latch device, said inner manually operable lever having a part arranged in opposing relation to a part of said swingable member to abut the same 15 at the same side of the pivotal axes of said lever and swingable member upon swinging movement of said inner manually operable lever in a second rotative direction thereby to move said swingable member in the same rotative direction to dispose said blocking means in opposing 20 position to said blocking portion, said blocking means when in said opposing position rendering said outer manually operable actuator ineffective to move said detent means out of holding position with respect to said latch device.
